UNITED STATES PATENT OFFICE.

WILLIAM DIETZ, OF CHICAGO, ILLINOIS, ASSIGNOR TO McCORD MANUFACTURING COMPANY, OF DETROIT, MICHIGAN, A CORPORATION OF MAINE.

RADIATOR-ASSEMBLING MACHINE.

1,024,124.

Specification of Letters Patent. Patented Apr. 23, 1912.

Application filed April 2, 1909. Serial No. 487,429.

To all whom it may concern:

Be it known that I, WILLIAM DIETZ, a citizen of the United States, residing at Chicago, in the county of Cook and State of

5 Illinois, have invented certain new and useful Improvements in Radiator-Assembling Machines, of which the following is a specification, reference being had therein to the accompanying drawing.

10 My invention relates to radiator assembling machines, and is especially designed to assemble the tubes and fins or plates of heaters, condensers, radiators, and other tubular devices.

15 The special object of the invention is to provide a new and improved machine for easily and quickly assembling in one operation all the tubes and fins or plates of devices of the character above noted and 20 which provides permanence and solidity of the assembled parts.

Another object is to provide a machine of this general character having means whereby successive sets of tubes and fins 25 may be placed in and removed from the machine in banks or blocks.

Other objects will be apparent from the accompanying disclosure.

30 The invention consists in the matters hereinafter described and then pointed out in the appended claims.

In the accompanying drawings Figure 1 is a plan view of an apparatus embodying 35 my invention, parts being broken away for purposes of illustration; Fig. 2 is a longitudinal central sectional view through the parts of Fig. 1; Fig. 3 is a side elevation of the device of Fig. 1; Fig. 4 is a view showing a front elevation of a fin or plate which 40 may be employed; Fig. 5 is an end view of the fin shown in Fig. 4; Fig. 6 is a view of a radiator tube which may be employed; Fig. 7 is a detail view showing a portion of the tube spindles with tubes thereon, and a 45 portion of the adjacent fin-frame with fin-combs and fins; Fig. 8 is a detail view on the line 8—8 of Fig. 7, some of the parts being broken away for purposes of illustration, and Fig. 9 is a detail sectional view 50 showing a set of tubes and fins assembled.

The several parts of the machine are mounted upon a suitable support such as a bed-plate which in the present form consists of an opposite pair of angle plates having horizontal and vertical webs 10 and 11

suitably connected at one end by a cross-piece 12 and at the other end adapted to be attached to a fin-frame as hereinafter described.

The bed-plate provides bearings at the 60 end adjacent the cross-piece for a drive shaft 13 which may be rotated from any suitable motor or source of power. The shaft 13 is provided with a worm 14 in position to engage a worm-wheel 15 located in 65 a yoke 16 at approximately the center of the cross-piece 12, and the worm-wheel 15 is provided with a central bore having a screw thread adapted to engage a correspondingly threaded endless-screw portion 70 of a rod 17, whereby the worm-wheel receives motion from the shaft 13 and imparts it to the rod to move the latter back and forth. The inner end of the rod 17 is rigidly connected with a tube-support 75 such as a truck or carriage 18 which extends across the width of the bed-plate and is provided with rollers 19 at each end adapted to support it in movable relation upon the horizontal webs 10 of the angle 80 pieces of the bed-plate.

The truck or carriage 18 carries a series of spindles 20 arranged and disposed upon the front side thereof in number and contour corresponding with the number and arrangement of radiator tubes which it is desired to assemble with their fins or plates. In the arrangement shown in Fig. 1, I provide four banks or rows of these spindles, 85 each bank or row comprising twenty spindles and preferably so arranged that the corresponding spindles of each bank will lie in the same vertical plane; it is of course to be understood that the number and disposition of these spindles may 90 be varied according to the pattern or design in which it is desired to assemble or mount the tubes in the radiator. In the preferred form of construction I preferably provide means for using the same 95 truck or carriage with successive sets of spindles, and for this purpose I mount the spindles upon a support or carrier 21 which may be detachably engaged with the truck or carriage. The spindle carrier may be 100 connected to the truck or carriage by any suitable means and for this purpose I have shown the carrier provided with a series of undercut vertical webs 22 adapted to detachably engage the correspondingly under- 110

cut grooves on the front face of the truck. In practice the spindles are provided with radiator tubes 23, preferably of brass, the spindles being suitably spaced apart for this purpose and sustaining the tubes against buckling or bending during the assembling operation.

At the end of the bed-plate opposite the cross-piece 12, I provide a fin-frame comprising a bottom 24 and connected vertical side pieces 25, the latter being secured to the vertical portions of the bed-plate by suitable bolts 26, and the former secured to a bench or table (not shown) by means of the wings 15 or ears 27.

The fin-frame is adapted to hold the fins or plates in position while they are being assembled upon the tubes 23, and in the preferred embodiment of my invention I provide a removable fin-holder which may be detachably supported upon this frame, it being understood that in practice a plurality of these holders will be successively employed so that sets of fins may be assembled 25 upon their associated holders while one of the holders is present in the machine, thereby enabling the machine to operate as rapidly as the holders are replaced and without stopping to refill the holder present on the 30 machine. In the broad aspect of this feature of my invention any suitable holder may be employed, and in the form shown it consists of the vertical back plate 28 having a horizontal web 29, and a front plate 30 of 35 less height than the back plate and lying below the plane of the lowest bank of spindles 20, as clearly shown in Figs. 2 and 7, the front and back plates being connected by any suitable means such as the headed bolts 40 31. The holder is provided with a series of comb-plates 32 extending across the width of the machine and suitably spaced apart along the lengths of the bolts 31 by spacing washers or fillers 33. The comb-plates are 45 approximately the height of the radiator fins 34 and the intercostal spaces between the teeth or fingers of the combs are arranged in alinement with each other and so disposed with respect to the perforations 50 35 of the fins that these spaces and perforations are in alinement along the length of the machine when these parts are assembled, the spacing washers 33 providing sufficient space between the comb-plates to receive the 55 radiator fins which in the present instance are rectangular copper plates of substantially the form shown in Figs. 4 and 5. The back plate 28 is also made comb-shaped corresponding to the comb-plates 32.

60 In the holder the fingers of the plates 32 form spacing and holding members for the fins, being spaced apart at intervals in one direction to permit the tubes to pass between them, and also spaced apart at substantially 65 right angles to said first direction to receive

the fins between them, the fin-spaces provided between the fingers being such that the fingers of each row engage the fins at each side of the openings in the fins, and the plates are secured together along their plane edges with their fingers or projecting portions in alinement in both directions by means of the bolts and spacing washers. When the fins are in the holder their edges engage the side plates 25 whereby they are 75 alined in position with their openings in line with the passages between the fingers.

The web 29 of the fin-holder may be detachably connected with the fin-frame by means of the removable screw bolts 36, and 80 the holder may be further held in place by means of an opposite pair of clamping plates 37 which may be detachably connected by screws 38 to the side pieces 25 and adapted to overlie the ends of the comb 85 plates and their associated fins as clearly shown in Figs. 1, 2 and 8 of the drawings.

When a number of fins 34 are assembled in position between the combs 32 of one of the holders, the corresponding openings 35 are in alinement and register with the intercostal spaces of the combs, and when the holder thus equipped with its quota of fins is assembled upon the frame the openings 35 and the spaces of the combs are in alinement 90 with the ends of the corresponding spindles 20 and their associated tubes 23, the spindles 20 being somewhat tapered at their ends as shown in Fig. 7, and the perforations 35 of the fins being somewhat flared or bell shaped in the preferred method of practice. When the holder with its associated fins is locked in position upon the frame, and the corresponding spindles are provided with tubes, suitable motion imparted to the truck 18 by means of its driving mechanism will cause the tubes to pass into or through the corresponding perforations of the fins, the tubes moving freely through the intercostal spaces of the combs 95 32 and the back plate 28 until the tubes are assembled in position upon their fins in substantially the relation shown in Fig. 9. After a set of tubes is inserted in their fins the spindles are withdrawn by retracting the 100 carrier 21, as by reversing the direction of rotation of shaft 13, and the fin holder may then be removed from the machine and the assembled fins and tubes comprising a radiator withdrawn simultaneously from the 105 fingers of the plates 32, the tubes passing laterally out through the open ends of the slots between the fingers. The holder composed of the connected front and back plates and the comb-plate provides means to rigidly support in fixed relation all the fins for a radiator, and also provides for simultaneously removing all the combs from between the fins and tubes of a complete radiator in one operation.

While the machine is operating to assemble one set of parts, another holder may be supplied with its fins and another set of spindles upon another carrier may be supplied with tubes so that when the first set is assembled a second set of fins and tubes may be quickly placed in position upon the machine to repeat the assembling operation, this rotation of the parts being carried out 10 with as many sets as may be necessary to enable the machine to be run to its highest capacity.

The machine also provides for quick and accurate assemblage at one stroke of all the 15 tubes and fins comprising a radiator, etc., and overcomes the friction resulting from the simultaneous assemblage of a plurality of closely fitting tubes and fins so that the parts are assembled in such intimate relation and frictional engagement that great 20 solidity and permanence of union results.

The machine may be supported upon any suitable bench or table (not shown).

Having described my invention, I claim:

25 1. In a device of the class described, a support for a plurality of tubes, a holder for a plurality of fins, and means to move one of the parts with relation to the other to assemble their associated fins on the 30 tubes.

2. In a device of the class described, a carrier for a plurality of tubes, a holder for a plurality of fins, and means to move the carrier with relation to the holder to 35 assemble their associated fins on the tubes.

3. In a device of the class described, a truck, a carrier for a plurality of tubes detachably mounted on the truck, a holder for a plurality of fins, and means to move 40 the truck with relation to the holder to assemble their associated fins on the tubes.

4. In a device of the class described, a bed plate, a truck movable thereon, a spindle-carrier on the truck, a fin-frame on 45 the bed plate, and a fin-holder on the frame comprising a series of spaced comb-plates.

5. In a device of the class described, a bed plate, a truck movable thereon, a detachable spindle-carrier on the truck, a fin-frame on the bed plate, and a detachable fin-holder on the frame comprising a series 50 of spaced comb-plates.

6. In a device of the class described, a bed plate, a truck movable thereon, a detachable spindle-carrier on the truck, a fin-frame on the bed plate, and a detachable fin-holder on the frame comprising a series 55 of comb-plates, a series of washers and bolts on which the washers and plates are alternately mounted.

7. In a device of the class described, a tube-support, means to detachably mount a bank of tubes thereon, a fin frame, means to detachably mount a bank of fins thereon, 60 and means to move one of the parts with

reference to the other to assemble their associated tubes in the fins.

8. In a device of the class described, a tube-support, a carrier detachably mounted thereon for a bank of tubes, a fin-frame, 70 means to detachably mount a bank of fins thereon, and screw mechanism to move one of the parts with reference to the other to assemble their associated tubes in the fins.

9. In a device of the class described, a bed plate, a truck thereon, a spindle carrier detachably mounted on the truck, a fin-frame on the bed plate, a fin-holder detachably mounted on the frame, a screw rod on the truck, a worm on the plate, and a multiple worm-wheel coöperating with the worm and screw rod to move the truck to 75 assemble the associated tubes in the fins.

10. In a device of the class described, a support for a plurality of tubes, a holder 85 for radiator fins, comprising a frame and a plurality of rows of spacing and holding members, said members being spaced apart at intervals in one direction to permit the tubes to pass therebetween and spaced apart 90 at substantially right angles to said direction to receive fins therebetween, and means for alining the rows of members in both directions on the frame, and means to move one of the parts to assemble their associated 95 fins on the tubes.

11. In a device of the class described, a support for a plurality of tubes, a holder for radiator fins comprising a series of plates each having a row of fingers spaced 100 apart at regular intervals to permit the tubes to pass therebetween substantially at a right angle to the plane of the plates, spacing members between the plates to permit insertion of fins between the rows of 105 fingers, means for alining the fingers of the plates, means for alining the fins, and means to move one of the parts to assemble the tubes in the fins.

12. In a device of the class described, a support for a plurality of tubes, a holder for radiator fins having openings to receive the tubes comprising a series of parallel plates each having a row of fingers projecting from one edge of the plate, said fingers 110 being in the plane of the plate and spaced apart at regular intervals to afford passages therebetween for the tubes, spacing members between the plates, means for alining the fingers of the plates, means for securing 115 the plates and spacing members to each other, means for alining the fins with their openings in line with the passages between the fingers, and means to move one of the parts to assemble the tubes in the openings 120 of the fins.

13. In a device of the class described, a support for a plurality of tubes, a holder for radiator fins having openings at regular intervals, spacing and holding members ar- 125

- 4
- ranged in parallel rows and spaced apart in one direction to form passages therebetween at intervals to permit the tubes to pass therethrough and spaced apart at substantially 5 right angles to said direction to receive the fins therebetween, means for rigidly supporting said members in fixed relation and for simultaneously removing the same from between the fins and tubes, an adjusting device 10 to engage the ends of the fins and adjust the same with their openings in alignment with the passages and guide openings, and means to move one of the parts to assemble the fins on the tubes.
- 15 14. In a device of the class described, a support for a plurality of tubes, a holder for radiator fins having openings, comprising a support and a series of rows of fingers attached at one end to said support and extending laterally therefrom across fins placed between said rows of fingers with the fingers of each row engaging said fins at each side of the openings to support and space the fins one from another, and means 20 to move one of the parts to assemble the tubes in the openings of the fins.
15. In a device of the class described, a support for a plurality of tubes, a holder for radiator fins comprising a series of parallel plates formed with slots extending inward from one edge forming spacing fingers to extend between adjacent fins and space the same one from another, means for securing said plates together along their 30 integral edge, and means to move one of the parts to assemble the tubes in the fins.
16. In a device of the class described, a support for a plurality of tubes, a holder for radiator fins comprising a series of parallel plates formed with fingers along one edge between which fingers of adjacent plates the fins are adapted to be placed, washers between the plates to space the fingers of one plate from those of the next 40 plate, and means for securing the plates together with the washers between, and means to move one of the parts to assemble the fins on the tubes.
17. In a device of the class described, a support for a plurality of tubes, a holder for radiator fins comprising a series of parallel plates each slotted inward from one edge to form a series of fingers, washers between the plates at their opposite edge, and bolts 45 extending through the plates and washers to secure the plates together, and means to move one of the parts to assemble the fins on the tubes.
18. An apparatus for assembling fins and tubes comprising a series of rows of members adapted to be projected between the series of perforated fins to support and space the same with the perforations in alignment with the spaces between the members of 50 each row, a frame for holding said members, and means for forcing tubes through the perforations in the series of fins in a single operation.
19. An apparatus for assembling a series of perforated fins upon tubes comprising a holder adapted to receive and hold a series of fins in spaced relation with their perforations in alignment and supporting said fins adjacent to each perforation, means for holding a series of tubes in alignment with 70 said aligned perforations, and a reciprocable plunger to engage the tubes and force the same through the perforations in the fins in a single operation.
20. An apparatus for assembling fins and tubes comprising a machine frame, a reciprocable plunger carried by said frame, a removable holder adapted to be placed within the frame in alignment with said plunger adapted to hold a series of fins in spaced relation, and means for actuating the plunger to force tubes through the series of fins in a single movement of said plunger.
21. An apparatus for assembling a series of radiator fins and tubes comprising a machine frame, a removable frame adapted to be supported by the machine frame, means within said removable frame for spacing a series of fins one from another, and means on the machine frame for forcing a series of tubes through said fins while held within said removable frame in alignment with said means.
22. An apparatus for assembling a series of radiator fins and tubes comprising a machine frame, a removable frame for carrying said tubes, a second removable frame adapted to be held in the machine frame in alignment with the other removable frame and adapted to hold a series of fins in alignment with said tubes and spaced apart, and means on the machine frame for forcing the tubes through the fins.
23. In a device of the class described, a support sustaining a plurality of tubes against buckling, a holder for perforated radiator fins comprising a series of plates each having a row of fingers spaced apart at regular intervals to permit the tubes to pass therebetween substantially at a right angle to the plane of the plates, spacing members between the plates to permit insertions of fins between the rows of fingers, and means to simultaneously move the tubes through perforations of the fins.
24. In a device of the class described, a support sustaining a plurality of tubes against buckling, a holder for radiator fins having openings to receive the tubes comprising a series of parallel plates each having a row of fingers projecting from one edge of the plate and spaced apart at regular intervals to afford passages therebetween for the tubes, spacing members between the plates, means for alining the fin- 125

gers of the plates, means for alining the fins with their openings in line with the passages between the fingers, and means to simultaneously move the tubes through the 5 openings in the fins.

25. In a device of the class described, a support sustaining a plurality of tubes against buckling, a holder for radiator fins having openings at regular intervals, spacing and holding members arranged in parallel rows and spaced apart in one direction to form passages therebetween at intervals to permit the tubes to pass therethrough and spaced apart at substantially right angles 10 to said direction to receive the fins therebetween, means for rigidly supporting said members in fixed relation and for simultaneously removing the same from between the fins and tubes, and means to simultaneously move the tubes through the openings 15 in the fins.

26. In a device of the class described, a support sustaining a plurality of tubes against buckling, a holder for radiator fins having openings comprising a support and 25 a series of rows of fingers attached at one

end to said support and extending laterally therefrom across fins placed between said rows of fingers with the fingers of each row engaging said fins at each side of the openings to support and space the fins one from another, and means to simultaneously move the tubes through the openings in the fins. 30

27. In a device of the class described, a support sustaining a plurality of tubes 35 against buckling, a holder for radiator fins having openings comprising a series of parallel plates formed with slots extending inward from one edge forming fingers to extend between adjacent fins and space the 40 same one from another, means for securing said plates together along their integral edge, and means to simultaneously move the tubes through the openings in the fins to assemble the tubes and fins in frictional engagement. 45

In testimony whereof I affix my signature in presence of two witnesses.
